U.S. PATENT DOCUMENTS

KR D212218-001 * 1/2021

Primary Examiner — Daniel J Domino

(74) Attorney, Agent, or Firm — Fox Rothschild LLP

(57)

CLAIM

The ornamental design for display screen with graphical user interface, as shown and described.

DESCRIPTION

1. Display screen with graphical user interface

1.1 : Front

(Continued)

The broken lines showing a display screen and elements of the graphical user interface illustrate portions of the article and form no part of the claimed design.

1 Claim, 1 Drawing Sheet
